Filed Oct. 12, 1966, Ser. No. 4,326

Term of patent 14 years

Int. Cl. D19—06

U.S. Cl. D74—17

FIG. 1

FIG. 2

FIG. 3

FIG. 4

FIG. 5

FIG. 6

FIGURE 1 is a left side elevational view of a writing implement showing my new design;

FIGURE 2 is a front elevational view thereof;

FIGURE 3 is a rear elevational view thereof;

FIGURE 4 is a top plan view thereof;

FIG. 5 is a fragmentary left side, side elevational view of another embodiment of the writing implement shown in FIG. 1 wherein the top is angled downwardly; and

FIG. 6 is a fragmentary left side elevational view of a further embodiment thereof wherein the top has been squared.

The undisclosed lower portions of FIGS. 5 and 6 present a similar appearance as the lower portions of the writing implement disclosed in FIGS. 1-3.

I claim:

The ornamental design for a writing implement, as shown and described.
